UNITED STATES PATENT OFFICE.

THOMAS HARRISON SYMINGTON, OF BALTIMORE, MARYLAND.

DRAFT-LINK.

1,097,739.

Specification of Letters Patent. Patented May 26, 1914.

Application filed February 5, 1913. Serial No. 746,297.

To all whom it may concern:

Be it known that I, THOMAS H. SYMINGTON, a citizen of the United States of America, residing at the city of Baltimore, State of Maryland, have invented certain new and useful Improvements in Draft-Links, of which the following is a specification.

This invention relates to railway draft gears, and particularly to a link and to the combination of parts including the link by means of which draft and buffing stresses are taken up and distributed.

In the various types of draft gear now in use, drawing stresses are transmitted to the rear follower or to the rear key by tension members which are parallel to each other and parallel to the longitudinal axis of the draft gear and of the car. These tension members, whether they be in the form of two links in each draft gear or in the form of the arms of a yoke, are so shaped that they are necessarily placed one at each side of the shock-absorbing member, extending from the point where they receive the tension of the draw-bar, backward to the rear key or the rear follower which is variously engaged by tension members in the different types of draft gear. With the tension members thus placed, one at each side of the shock-absorbing member and immediately within the draft beams, they are spaced well apart and the drawing and buffing forces and the reaction due to the inertia of the load are applied at points which are comparatively distant in the direction of the length of the keys and followers. Therefore the keys and followers are necessarily constructed to withstand a considerable bending moment and shearing stress. This is particularly true in the case of the rear follower or key which in a large number of draft gears now offered to the trade must receive and transmit the entire shock in buffing and drawing. In drawing this member applies the stress applied to it to the shock-absorbing member, while in buffing the thrust is received by it from the shock-absorbing member and transmitted to the frame.

The draft links and various members which cooperate therewith in receiving and distributing the buffing and drawing stresses in the draft gear described herein, are constructed particularly with a view to so distributing these stresses that while the weight

of the draft gear is considerably reduced, its efficiency and the simplicity of the structure are at the same time increased, and this reduction in weight applies not only to the links themselves but to the followers, keys and other coöperating parts. More particularly described, the links which are an important feature of the invention, instead of being longitudinally-extending bars or plates apertured at various points to admit the keys or to engage the followers, such as are ordinarily employed, are constructed each in the form of an elongated loop having a lateral dimension sufficient to admit the shock-absorbing member. The links thus formed, while they are preferably placed at their forward ends one on each side of the draw-bar, are not necessarily parallel to each other or to the axis of the draft gear when in operative position, as they are of sufficient dimension to admit and inclose the whole or a part of the shock-absorbing member. Thus they may be conveniently placed so that they converge toward the rear, and the drawing stress is thus applied to the rear follower at points alined in a longitudinal direction with the bearing which that follower takes on the rear end of the shock-absorbing member. Thus in drawing, the stress applied to the rear follower takes the form of compression rather than shearing or bending moment. In this way the tendency to bend or shear the rear follower in drawing is entirely eliminated and it is consequently rendered possible to make the follower of less weight. Further, by forming the links as described and placing them so that they converge toward the rear, it is made possible to increase the lateral dimensions of the draw-bar stops, so that they extend inward to points which are substantially alined in a longitudinal direction with points on the rear bearing face of the shock-absorbing member. Thus the buffing as well as the drawing stresses applied to the rear follower take the form of compression rather than bending moment.

In the accompanying drawing I have illustrated draft links of two different types, both embodying the features of the invention in the preferred form.

In these drawings Figure 1 is a plan of the device in its preferred form. Fig. 2 is a section of the same taken on the line 2, 2 of Fig. 1. Fig. 3 is a plan of a draft

link of a slightly different type embodying the invention. Fig. 4 is a section taken on the line 4, 4 of Fig. 3.

Referring to the drawings by numerals, each of which indicates the same or equivalent parts in the different figures, the draft gear includes a draw-bar 1 and a shock-absorbing member 2. In Figs. 1 and 2 there are shown a front key 3 and a rear key 4 mounted in suitable slots 5 and 6 in the draft beams 7 and cheek plates 8, the rear key preferably serving as a front stop. The buffing stresses are applied to the shock-absorbing member 2 by means of a front follower 9 placed between the rear end of the draw-bar and the front end of the shock-absorbing member 2. This follower is slotted to receive and supported on the rear key 4. At the rear the drawing stresses are communicated to the shock-absorbing member 2, and the buffing stresses are transmitted to the frame by means of a rear follower 10 and rear stops 11. The drawing stresses are transmitted from the drawbar in this instance through the forward key 3 to the rear follower 10 by means of links 12, which, as stated, are an important feature of the present invention. These links, as seen in plan in Fig. 1, while they are placed one on each side of the drawbar at the forward end, converge toward the rear so that at this point they approach the center line of the draft gear, and in order that they may be so placed in the structure shown, they are constructed each in the form of an elongated loop, see Fig. 2, the loop being placed with its opening in a vertical plane. In the present instance, as illustrated, the forward end of each link must engage the forward key 3 and receive from this key the drawing stresses applied to the drawbar, and to this end in order that the loop may be so formed as to resist the stresses applied without being distorted, the forward portion of the loop is reduced at 13 as shown in Fig. 2 until the internal curve at its extreme forward end is only sufficient to conform to the corresponding curve of the key. From this point the arms of the loop diverge, as shown, at an angle preferably about 30° until the greatest lateral dimension of the loop is reached at 14. From this point rearward the sides or legs of the loop are shown as parallel, and to prevent collapse or distortion of the loop under extreme tension, it is supported at the points 14 by a transverse member 15, though it may be otherwise conveniently braced or strengthened within the scope of the invention. At the rear the loop is preferably curved as shown at 16 to give the most convenient and efficient disposition of the metal, and to fill the curved portion and transmit the drawing stresses to the follower 10, which is most conveniently and

economically made flat, a filler member 17 is provided. This also serves to position the links. To this end it is constructed with a central rib or spacing member 18 and a head 19. The rib 18 serves to separate the two links and the head 19 overlies them at the rear and prevents displacement of the filler as well as of the links. Where the links bear on the filler, inwardly inclined seats 20 are provided which conform to the corresponding surfaces of the links. These tend to throw the links inward toward the rib 18 and to position the links in relation to the filler. Also the rear stops 11 extend inward toward the links sufficiently so that the latter cannot be displaced laterally and thrown out of engagement with the filler.

In Fig. 3 a draft gear has been illustrated which is provided with front stops 21 and a front follower 22 to engage the stops. This gear has a single key 23 which is seated in the draw-bar 1 and is engaged by the forward ends of the links 24, this engagement being similar to that described in connection with Figs. 1 and 2, but to provide for the use of the front stops 21 and the front follower 22, and the consequent elimination of the rear key 4, the link 24 is flattened laterally at 25, as seen in Fig. 3, and correspondingly expanded in the vertical plane at the same point, see Fig. 4. This gives the link substantially the same cross-sectional area and the same strength that it has as formed in Figs. 1 and 2, but so reduces its lateral dimension in a horizontal direction that it provides sufficient room for the front stop 21. In other features this draft gear is substantially similar to the one illustrated in Figs. 1 and 2, and in this connection I desire to have it understood that both of the draft gears are illustrated for the purposes of description in order to make the nature and the operation of the device of the invention clear, and that the numerous details set forth are not essential to the invention.

By reference to Figs. 1 and 3 it will be clearly apparent that the bearing points 20 of the links on the filler 17 are in alignment with the rear bearing face 26 of the shock-absorbing member, so that the rear follower in drawing is placed under compression by the action of the links and is subject to no shearing and bending stresses, and it will also be apparent that the rear stops 11 at their outer portions are substantially in alignment with points on this bearing surface 26, so that in buffing the rear followers are subject to compression stresses only, and not to bending moment. Thus the followers may be of lighter construction than heretofore. Further, the draft links themselves as shown and described may be of lighter construction than the draft links previously used, and it will also be apparent that the

whole draft gear is simple in form and efficient, in that the stresses are so distributed that they are resisted to the best advantage.

I have thus described specifically a single embodiment of my invention in order that its nature and operation may be clearly understood. However, the specific terms herein are used in their descriptive rather than in their limiting sense and the scope 10 of the invention is defined in the claims:

I claim—

1. A draft gear consisting of a draw-bar, a shock-absorbing member, two converging links, each having its lateral surfaces flat 15 and the cross-section of its arms substantially uniform, means connecting the links at their forward ends to the draw-bar, means for applying the drawing stresses transmitted to the links by the draw-bar to 20 the rear end of the shock-absorbing member, and means for applying the buffering stresses to the shock-absorbing member.

2. In a draft gear, a draw-bar, two links, a shock-absorbing member, the links being 25 flat as to their lateral surfaces, having their arms of substantially uniform cross-section, and having an opening sufficient to receive and admit the shock-absorbing member, and placed so that they converge from the 30 front to the rear and partially inclose the shock-absorbing member, and means for transmitting the drawing stresses to the links.

3. In a draft gear, a draw-bar, two links, 35 a shock-absorbing member, the links having an opening sufficient to receive and admit the shock-absorbing member and being placed so that they converge from the front to the rear, the lateral surfaces of the links 40 being flat and the arms of the links being of uniform cross-section, the rear ends of the links being alined in the direction of the longitudinal axis of the draft gear with the rear bearing surface of the shock-absorbing 45 member.

4. In a draft gear, a draw-bar, two links, a shock-absorbing member, the links having an opening sufficient to receive and admit the shock-absorbing member and being 50 placed so that they converge from the front to the rear, and means for transmitting the

drawing stresses applied to the links from the latter to the rear end of the shock-absorbing member, the rear ends of the links being alined in the direction of the longitudinal axis of the draft gear with the rear bearing surface of the shock-absorbing member.

5. In a draft gear, a draw-bar, two links, a shock-absorbing member, the links having an opening sufficient to receive and admit the shock-absorbing member and being placed so that they converge from the front to the rear, and means for transmitting the drawing stresses applied to the links from the latter to the rear end of the shock-absorbing member, said means having inclined seats for positioning the rear ends of the links, the rear ends of the links being alined in the direction of the longitudinal axis of the draft gear with the rear bearing surface of the shock-absorbing member.

6. In a draft gear, a slotted draw-bar, a shock-absorbing member, a key seated in the draw-bar slot, links each in the form of an elongated loop reduced at its forward end inclosing the key at that end and placed one on each side of the draw-bar, said links converging toward the rear and having their rear portions alined in the direction of the longitudinal axis of the draft gear with the rear bearing surface of the resilient member.

7. In a draft gear, a slotted draw-bar, a shock-absorbing member, a key seated in the draw-bar slot, links each in the form of an elongated loop reduced at its forward end inclosing the key at that end and placed one on each side of the draw-bar, said links converging toward the rear inclosing a portion of the shock-absorbing member, and having their rear portions alined in the direction of the longitudinal axis of the draft gear with the rear bearing surface of the resilient member.

Signed by me at Baltimore city, State of Maryland, this 3rd day of February, 1913.

THOMAS HARRISON SYMINGTON.
